UNITED STATES PATENT OFFICE.

ARTHUR H. HUTCHINSON, OF ATLANTA, GEORGIA.

REFRIGERATING APPARATUS.

Application filed April 19, 1924. Serial No. 707,688.

To all whom it may concern:

Be it known that I, ARTHUR H. HUTCHINSON, a citizen of the United States, residing at Atlanta, in the county of Fulton and 5 State of Georgia, have invented certain new and useful Improvements in Refrigerating Apparatus, of which the following is a specification, reference being had to the accompanying drawings.

10 This invention relates to improvements in refrigerating apparatus and more particularly to an improvement of the type of apparatus employing partially submerged ice cans in the commercial production of ice and wherein the use of air in agitating the water of the can while freezing to prevent formation of white ice is resorted to.

15 It is well known to those familiar with the art that in apparatus of this character it is necessary to employ dehydrated air in the feed system for the reason that otherwise the moisture of the air would freeze within the pipes, due to the low temperature to which they are subjected, resulting 20 in the cutting off of the air and accordingly in the formation of white ice in the cans. It is further well known that air which has been passed through cold water is dehydrated and it is, therefore, an important 25 object of this invention to conduct the air which has already been passed through the water of the cans back to the blower feeding the water to the drop pipes or corner pipes of the can, whichever may be employed for use, thus eliminating the necessity 30 for a dehydrating apparatus in the line.

35 A further and more specific object of the invention is to provide a feed and return line so constructed and operated that the return line forms a support for an air hose leading from the feed line to the air pipe of the can when not in use.

40 A still further object of the invention is to provide an apparatus of this character in which the air from the air pipes is fed through the return pipe to the blower when the device is not in use, thus preventing the loss of any considerable amount of air or 45 the intake into the system through the openings of the return pipe of any appreciable amount of undehydrated air.

50 A still further object of the invention is to generally improve the construction of the type of frame-work employed above the brine tanks in this type of refrigerating

apparatus to render the same less likely to breakage and destruction and generally more efficient.

These and other objects I attain by the 60 construction shown in the accompanying drawings, wherein for the purpose of illustration is shown a preferred embodiment of my invention and wherein:—

Figure 1 is a perspective view of a portion 65 of the upper portion of a brine tank employed in ice making showing a construction in accordance with my invention, the cover being removed;

Figure 2 is a vertical sectional view 70 through the apparatus with the cover in place;

Figure 3 is a side elevation of the T employed for attaching the air hoses to the 75 feed pipe;

Figure 4 is a side elevation of the elbows employed at the free ends of the air hoses for connecting the same with the air pipes or with the exhaust pipe;

Figure 5 is a perspective of the plate 80 employed for supporting the pipes and maintaining the partitions 12 in position.

Referring now more particularly to the drawings, the numeral 10 indicates main division girders arranged within the upper 85 surface of the brine tank (not shown) and preferably extend longitudinally of the brine tank. Arranged between adjacent girders 10 are supplemental division girders 11 90 paralleling the girders 10 but having their upper surfaces arranged below the plane of the upper surface of the girders 10. The space between girders 10 and adjacent girders 11 is subdivided into can spaces by transverse partitions 12 each having one end 95 thereof let into the main girder as indicated at 13. As a means of attaching the adjacent ends of partitions 12 abutting opposite sides of intermediate girders 11, I provide spaced plates 14 abutting opposite sides of adjacent 100 ends of the plates 12 and resting at their lower ends upon the upper surfaces of the girders 11. These plates are held together by bolts or other securing means, indicated at 15, and tend to prevent any movement of 105 the partitions 12 which would destroy the same.

Each pair of plates 14 is provided in its lower edge with a notch 16 and in its upper 110 edge with a notch 17. Seated upon the upper surface of the intermediate girders are conduits 18 leading to the intake of a blower

as indicated, the blower not being herein disclosed. These conduits extend through the notches 16 and are held in position upon the upper surface of the girders 11 by the plates 14. The upper notches 17 of a second conduit 19 parallel the conduit 18, this conduit communicating with the exhaust of the blower. The plates 14 are of sufficient length that the conduits 18 and 19 having a space therebetween permitting communication between adjacent can compartments C disposed at opposite sides of the girders 11.

To the under surface of the pipe or conduit 19, preferably approximately midway of its length, between adjacent transverse partitions 12 a T 20 is connected to the outlets of which are connected air hoses 21 each having an L 22 at its free end, the outlet end of the L being provided with a tapered exterior as shown at 23. In the upper surface of the pipe or conduit 18 tapered openings 24 are formed corresponding in number to the air hoses and having the taper of the openings such that the nozzle of the L fits snugly therein. It will, of course, be understood that the drop pipe P employed in the can will be formed at its upper end to receive this same nozzle.

In the use of my apparatus, when the cans have been placed in position in the compartments C at opposite sides of the the lesser partitions 11, the air hoses 21 have their nozzles 23 disengaged from the openings 24 of the pipe 18 and engaged with the drop pipes of their respective cans. The cover of the compartments C is then applied. At this time in operation air will be forced from the pipes 19, through the air hoses 21, to the air pipes of the tanks and leaving these air pipes will agitate the water in passing upwardly through the water and collect beneath the cover plate of the compartments C, from which point it will be withdrawn through the openings 24 into the conduit 18 to be returned to the blower. When the freezing is completed the cover plates of the compartments are removed, the air hoses 21 disengaged from the air pipes of the tanks and engaged in the openings 24. It will be obvious that this operation will take but a very short time and there will accordingly be but a very small amount of outside air drawn into the pipe 18 before the air hoses are engaged therewith. It will furthermore be noted that these air pipes when engaged in the openings 24 will be positioned in the pipes 18 and 19 and accordingly not in the way of the ice tanks as they are removed from the brine. It will be obvious that the construction herein illustrated is capable of a considerable range of change and modification without materially departing from the spirit of my invention and I accordingly do not limit myself to such specific structure as herein-

before set forth except as hereinafter claimed.

I claim:

1. In ice making apparatus having compartments for the reception of water tanks, the water tanks each being provided with an air pipe, the compartments being provided with covers, a pair of conduits associated with each tank, one of said conduits being connected with the exhaust and the other with the intake of a blower, an air hose connected at one end to the first named conduit and having its opposite end engageable with the air pipe of the water tank, the last named conduit having an opening communicating with the compartment beneath the cover thereof, the last named end of the air hose being engageable in said opening.

2. A division structure for ice tanks comprising parallel main division girders, intermediate girders disposed between and paralleling the main girders and having their upper surfaces disposed in a plane beneath the plane of the upper surfaces of the main girders, a conduit resting upon the upper surface of each intermediate girder, transverse partitions let into the main and intermediate girders and having their upper surfaces flush with the upper surface of the main girders, plates resting at their lower ends upon the intermediate girders and clampingly engaging adjacent ends of the upper portions of the transverse partitions, said plates being provided in their lower ends with notches permitting the passage of said conduit, said plates being provided in their upper edges with notches receiving a second conduit and supporting the same above and in spaced relation to the first named conduit.

3. A dehydrated air feeding system for the air pipes of the water cans of refrigerating apparatus comprising a can compartment having a removable cover at its upper end, conduits leading to and from a blower communicating with the compartment, the communication of the conduit leading to the compartment with the compartment including a flexible hose having at its free end means for engaging it with the air pipe of the can to direct air therethrough, the communication of the other conduit with the compartment comprising an opening formed in the conduit in which the means for engaging with the air pipe are engageable.

4. A division structure for ice tanks comprising parallel main division girders, intermediate girders disposed between and paralleling the main girders and having their upper surfaces disposed in a plane beneath the plane of the upper surfaces of the main girders, a conduit disposed above the upper surface of each intermediate girder, transverse partitions let into the main and intermediate

girders and having their upper surfaces flush with the upper surface of the main girders, plates resting at their lower ends upon the intermediate girders and clamping-
ly engaging adjacent ends of the upper por-
tions of the transverse partitions, said con-
duit extending through said plates.

5. A division structure for ice tanks comprising parallel main division girders, intermediate girders disposed between and paral-
leling the main girders and having their up-
per surfaces disposed in a plane beneath the
plane of the upper surfaces of the main
girders, a conduit disposed above the upper

surface of each intermediate girder, trans-
verse partitions extending between the main
and the intermediate girders and secured to
each thereof, the upper surfaces of said
transverse partitions being arranged in a 15
plane above the upper surfaces of the inter-
mediate girders, and means supported from
the intermediate girders securing together
adjacent ends of the upper portions of the
transverse partitions and providing a sup- 20
port for said conduit.

In testimony whereof I hereunto affix my
signature.

ARTHUR H. HUTCHINSON.
